UNITED STATES PATENT OFFICE

153,728

DESIGN FOR A HOUSE SHOE

John B. Reinhart, Jr., and Joseph B. Ruebel,
Farmington, Mo., assignors to Trimfoot Com-
pany, Farmington, Mo.

Application January 26, 1949, Serial No. 493

Term of patent 7 years

(Cl. D7—7)

To all whom it may concern:

Be it known that we, John B. Reinhart, Jr., and Joseph B. Ruebel, citizens of the United States, residing at Farmington, Missouri, have invented a new, original, and ornamental Design for a House Shoe, of which the following is a specification, reference being had to the accompanying drawings, forming part thereof.

Figure 1 is a side view of a house shoe, embodying the design.

Figure 2 is a perspective view of the house shoe shown in Figure 1.

We claim:

The ornamental design for a house shoe, substantially as shown.

JOHN B. REINHART, JR.
JOSEPH B. RUEBEL.
